TUBE OR BALL MILL WITH COOLED TRUNNION

Filed Sept. 15, 1943

UNITED STATES PATENT OFFICE

2,456,073

TUBE OR BALL MILL WITH COOLED
TRUNNIONRay C. Newhouse, Wauwatosa, Wis., assignor to
Allis-Chalmers Manufacturing Company, Mil-
waukee, Wis., a corporation of Delaware

Application September 15, 1943, Serial No. 502,427

1 Claim. (Cl. 241—67)

1

This invention relates to ball mills for the comminution of materials in a heated condition.

It has been previously known in the art to grind heated materials both dry and in a liquid medium by tumbling them about with or without steel balls or other grinding media. It is also known to cool the bearings of such mills in order to keep bearing temperatures within a range for efficient operation.

An object of this invention is to provide an improved mill for heated materials with bearing trunnion structure spatially insulated from the mill end and from material feed and discharge conduits operating in contact with the heated materials and mediums.

Another object of the invention is to provide for the circulation of gaseous cooling medium through the space between a mill end with its feed or discharge conduit and a bearing trunnion coaxially surrounding the material conduit.

It is a further object of this invention to provide a simple inexpensive and effective structure for maintaining an effective insulation of a ball mill bearing trunnion from parts of such mill operating in contact with heated materials which continuously pass through the bearing trunnion.

Specifically the invention consists in a structure providing a clear space for the free flow of air between a mill supporting bearing trunnion and mill end and the parts of the mill operating in continuous contact with heated materials being ground in the mill and passing through the bearing trunnions.

Other and still further objects may appear from the following description with reference to the accompanying drawing, in which:

Fig. 1 is a vertical longitudinal view of a ball mill according to the invention; and

Fig. 2 is a fragmentary top elevation showing a portion of the edge of the heads and flange of the mill of Fig. 1.

Rotating mill drum 1 is supported by bearing trunnions 2 on the heads 3. The bearing trunnions 2 rest in bearings 4. Within the head 3 at the feed end of the mill and spaced from head 3 is an end wall or liner 6 which closes the mill and carries a material feed conduit 7 extending coaxially through the feed trunnion 2 in spaced relation. A suitable rotary material feed drum 8 with a spiral scoop, as well known in the art, is attached to the end of conduit 7. Material chute 9 is arranged to supply material to such a drum 8 in a well known manner. Fluid feed pipe 11 extends through drum 8 to sup-

ply fluid to the grinding space within the mill.

The mill 1 may be provided with a suitable division head 13 if it is desired to divide the grinding space into coarse and fine grinding chambers.

At the discharge end a positive discharging head 14 similar to that disclosed in R. C. Newhouse U. S. Patent 2,259,769 is arranged to discharge material from the grinding space into

10 the discharge conduit 17 which extends from the discharge end wall or liner 16 closing the grinding space in coaxially spaced relation to bearing trunnion 2. The end liner 16 may be secured adjacent the said discharge head 14 and be spaced annularly from the end head 3. A stationary housing 18 receives the ground product and carries a valve 19 for a purpose disclosed in above cited U. S. Patent 2,259,769. Flanges 12 are provided on the ends of the mill drum for 20 securing the end liners 6 and 16.

As shown in Fig. 2 the supporting heads 3 are bolted to flanges 12. The end liners 6 and 16 may be secured between flanges 12 and heads 3, and may be spaced from heads 3 around their peripheries by a plurality of arcuate bosses 21 on heads 3, in such a manner that recesses or openings 22 are formed to communicate with the annular space between said end liners 6 and 16 and supporting heads 3. Bolts 23 may be used 30 to secure the end liners and plates to flanges 12.

In operation the mill 1 is arranged to be charged with a quantity of highly heated materials, as for instance, a mixture of coal or other solid material supplied through chute 9

35 and normally high viscosity fluid such as bunker C fuel oil. This fluid has been heated to a degree sufficient to lower its viscosity to permit ready flow as, for instance, 325 degrees Fahrenheit or more. The mixture is tumbled as in ordinary ball mill wet grinding and a fluid suspension of fine ground solids in oil is produced.

The highly heated mixture flowing through the trunnions and drum of the mill ordinarily would overheat the bearing trunnions and would, ultimately, causing bearing failure. The mill supporting heads and trunnions are spatially isolated from the highly heated end liners and trunnion liners or material conduits. This prevents direct conduction of heat to the bearing except 45 through the limited and circuitous path offered by bosses 21 and heads 3.

Free flow of cooling media through the space between the end liners 6 and 16 and the corresponding structural heads 3, as shown by arrows 50 in Fig. 1, is also provided for. This space being

open to atmosphere, flow is induced by centrifugal force coupled with gravity draft due to contact of the air cooling fluid with the highly heated parts 6, 7, 16 and 17.

The invention has at once provided for insulation and flow cooling medium between the surfaces of a ball mill which may be used for heated material and the structural end heads and hollow bearing trunnions.

While a particular embodiment of the invention has been illustrated and described it will be understood that such modifications and equivalents as may readily occur to persons skilled in the art are included within the scope of the invention which is limited only by the scope of the appended claim.

It is claimed and desired to secure by Letters Patent:

In a mill for treating hot materials, a fluid-tight drum shell having an imperforate annular end wall with an outwardly extending tubular extension of smaller diameter than said shell, said shell and end wall forming an impervious material treating container and said tubular extension forming a material conduit opening into said container, means to support said container for rotation comprising a hollow trunnion of a diameter intermediate the diameter of said tubular extension and said drum shell in coax-

ially spaced relation to said tubular extension, said trunnion being physically connected in supporting relation to said container solely by a structural end head axially spaced from said end wall except adjacent to the outer periphery of said end wall and passages opening radially outwardly from the space between said end wall and said structural end head to provide for free circulation of cooling fluid through the space between said end wall and said structural end head and hollow trunnion.
